UNITED STATES PATENT OFFICE.

CARL J. HAZELTON, OF WORCESTER, MASSACHUSETTS, ASSIGNOR TO AMERICAN NARROW FABRIC COMPANY, A CORPORATION OF MASSACHUSETTS.

DETACHABLE CONNECTER FOR HOSE SUPPORTERS.

Application filed June 20, 1922. Serial No. 569,590.

This invention relates to a detachable device for connecting two parts, as for example, an elastic and non-elastic tape of a hose supporter, suspender, or the like.

5 The principal objects of the invention are to provide a readily detachable oblong member provided with two bars, each adapted to pass through a sewed loop in the end of a tape or elastic to be connected, and having 10 means which will permit of the ready separation of the device at one end, but will prevent accidental separation, and especially to provide a construction for this purpose which will be very simple and inexpensive 15 and involve no complicated parts projecting materially from the tapes or the like to be connected.

Reference is to be had to the accompanying drawings, in which—

20 Fig. 1 is a front view of a hose supporter shown with a preferred embodiment of this invention applied thereto;

Fig. 2 is an edge view of the same;

25 Fig. 3 is a front view showing the connector open for detachment;

Fig. 4 is a front view of the connector itself on enlarged scale; and

Fig. 5 is a transverse sectional view on the line 5—5 of Fig. 1.

30 I have shown the invention as applied for the purpose of connecting two pieces of tape 10 and 11, one preferably elastic and the other non-elastic, or of any other desired character.

35 It has been customary heretofore to form loops in the adjacent ends of the two pieces to be connected by doubling them over on themselves and sewing the edge back to the body of the tape. This forms two parallel 40 horizontal passages which have been connected by a pair of bars extending through them integrally connected together at one end and at the other end either having the two ends connected or else of such stiff material as to cause them to remain in fixed condition under all ordinary strains to which the article is to be subjected, or else complicated devices have been employed when detachability was desired.

45 This invention involves the use of the main part of the said wire and with a very simple detachable means thereon for securely holding the free end with respect to the other end of the wire and yet allowing it 50 to be detached readily.

The main part of the connector comprises a wire 12 bent or doubled on itself to form two parallel bars 13 and 14. The bar 13 is shown as a little shorter than the bar 14 and as having secured to it a sheet metal casing 60 15 which forms a permanent part of the bar 13. This casing is pressed on the end of the latter bar and is hollow throughout. Of itself it is of U-shape construction with one leg longer than the other, that is the one 65 connected with the wire 12. The other leg is shorter and is open on its side adjacent to the longer leg to provide a longitudinal passage 16 for the reception of the end of the bar 14 of the wire. This opening is long 70 75 enough to extend a little beyond the end of the wire bar 14.

It will be seen that the casing 15 is firmly and permanently fixed on the end of the wire and that the bar 14, which is ordinarily set 80 to swing back as shown in dotted lines in Fig. 4, can be bent down under the end of the short leg of the casing 15 until it springs into the opening 16. Then its own resiliency will hold it in that position. When it is desired to detach it, it is pushed down toward the other bar and pressed to the side, when it will automatically spring back to the dotted line position. In this position the bar 13 preferably is secured through the 85 loop in one of the tapes or elastics 10 by sewing the latter over it. It extends beyond the loop as clearly shown. The bar 14 is freed from the casing 15 and then put through the loop in the other tape or elastic 11. When 90 it is swung down into the full line position as shown in Figs. 1 and 4 it will hold the two parts 10 and 11 together as long as may be desired, and there will be no tendency to spring apart or become detached at the free 95 end.

Although I have illustrated and described only one form of the invention I am aware of the fact that modifications can be made therein by any person skilled in the art without departing from the scope of the invention as expressed in the claim.

Therefore I do not wish to be limited to all the details of construction shown and described herein, but what I claim is:—

105 As an article of manufacture, a detachable connector for a hose supporter consisting of two parts of a U-shaped wire having its two bars parallel with each other and directly connected and one longer than the other and 110

both ends of the wire cylindrical and cut off square and a sheet metal cylindrical casing also of U-shape, and having its longer leg fixedly and permanently secured to the end of the shorter bar of the wire, and the other parallel therewith, and open on the inner side, whereby the longer bar of the wire will

be capable of being sprung into said opening, and when so located will be held therein by the sides of the casing beyond the 10th opening.

In testimony whereof I have hereunto affixed my signature.

CARL J. HAZELTON.
